UNITED STATES PATENT OFFICE.

FRANK T. HOPKINS AND GEORGE PAINTER, OF ST. LOUIS, MISSOURI, ASSIGNEES TO
THOS. CUSACK CO., A CORPORATION OF NEW JERSEY.

DESIGN FOR A SIGN.

45,838.

Specification for Design.

Patented May 26, 1914.

Application filed March 4, 1914. Serial No. 822,514. Term of patent 3½ years.

To all whom it may concern:

Be it known that we, FRANK T. HOPKINS and GEORGE PAINTER, both citizens of the United States, and residents of the city of St. Louis and State of Missouri, have invented a new, original, and ornamental Design for Signs, of which the following is a specification, reference being had to the accompanying drawing forming part thereof.

In the drawing Figure 1 represents a view

in perspective of our novel sign design. Fig. 2 is a view in end elevation thereof.

We claim:

The ornamental design for a sign, as shown.

FRANK T. HOPKINS.
GEO. PAINTER.

Witnesses:

W. R. STOVERS,
W. E. RUSSELL.
